FIG. 1 is a front elevational view of a wall hanging level retention brace showing my design.

FIG. 2 is a rear elevational view of the design shown in FIG. 1

FIG. 3 is an enlarged left side elevational view thereof being used in connection with a wall hanging.

FIG. 4 is a right side elevational view thereof being used in connection with a wall hanging.

FIG. 5 is a left rear perspective view thereof shown in FIGS. 1-5.

FIG. 6 is a right front perspective view thereof shown in FIGS. 1-5.

FIG. 7 is a left side elevational view, similar to that of FIG. 3, thereof used in connection with a wall hanging.

FIG. 8 is a rear elevational view thereof being used in connection with a wall hanging; and,

FIG. 9 is a top plan view thereof.
The brace is shown broken away in the middle horizontally and vertically to indicate indeterminate length.**1 Claim, 2 Drawing Sheets**| (56)	References Cited
